IMPROVED SCAFFOLD BRACKET.

HIRAM BECKWITH, OF GRASS LAKE, MICHIGAN.

Letters Patent No. 60,122, dated December 4, 1866.

SPECIFICATION.

TO ALL WHOM IT MAY CONCERN:

Be it known that I, HIRAM BECKWITH, of Grass Lake, in the county of Jackson, and State of Michigan, have invented a new and useful improvement in Scaffold Brackets; and I do hereby declare that the following is a full, clear, and exact description thereof.

The object of my invention is to prevent the occurrence of the accidents which so often happen to those engaged in erecting buildings in consequence of the insecure scaffolds upon which they stand; and this I propose to do by furnishing portable fixtures of iron or some other strong material which may be readily affixed to the side of the building, and upon which the scaffolding can be laid. And to enable others skilled in the art to make and use my invention, I will proceed to describe its construction, reference being had to the accompanying drawings, forming a part of this specification, and to the letters of reference marked thereon.

A represents the side of a building; B is the tie rod; C is the rail, and D is the brace. The rail, C, and the brace, D, are connected together by a joint as seen at *a*, in the drawing; this joint is permanent, allowing the two pieces to be folded together when not in use. Other forms of joint than the one represented might answer the same purpose. There is a screw-thread cut on the end of the rail at *b*. The tie, B, has a hole or eye through its upper end at *c*; at its lower end there is a hook, *d*, which hook has a socket or recess formed in it for the reception of the end of the brace, and which is represented as being below the dotted line, *e*. This tie also has a point or gaff formed on its back, as seen at *f*. The lower end of the brace, D, is formed to enter the socket in the tie, where it is secure from being displaced except by raising the end of the rail at *a*. This connection may be made by a screw-bolt going through both the brace and the tie. To attach the bracket to a building, the tie is slipped on to the rail, as seen in the drawing, but the connection at the bottom is not then made. The rail is screwed into the timber, post, or stud of the building, so that it shall be perfectly secure, the rail being in a horizontal position, as represented in the drawing. The back side of the tie, B, resting against the building and the point, *f*, enters the timber for the purpose of preventing the tie from moving laterally, or to keep it steady. When the rail is firmly secured to the building, and the tie placed in position, as described, the lower end of the brace is placed in the socket, and the bracket is ready to receive the scaffolding. The advantages gained by the use of this bracket are numerous, its perfect reliability being perhaps the most important, but it also saves lumber and requires no nails, while the time saved in erecting a scaffold is a very important item. It is also portable, and a well-made set would be almost indestructible.

Having thus described my invention, what I claim as new, and desire to secure by Letters Patent, is—
The tie B, the rail C, and the brace D, when constructed and combined substantially as herein shown and described for the purposes set forth.

HIRAM BECKWITH.
